UNITED STATES PATENT OFFICE.

ARRELIUS M. McSPADDEN, OF ST. LOUIS, MISSOURI.

PORTABLE HOLDER FOR GREASE CONTAINERS.

Application filed April 15, 1921. Serial No. 461,613.

To all whom it may concern:

Be it known that I, ARRELIUS M. McSPADDEN, a citizen of the United States, residing in the city of St. Louis and State of Missouri, have invented new and useful Improvements in Portable Holders for Grease Containers, of which the following is a specification.

This invention relates to apparatus for facilitating the charging of grease into gear casings, for example, the differential or transmission casings of automobiles. The present method of effecting this is to provide a charging device, known popularly as a grease gun; a quantity of grease is placed in the barrel of the grease gun and then forced into the differential casing. This method necessitates handling the grease from the container in which it is furnished.

The general object of my invention is to overcome the necessity for handling the grease. I provide a special container for the grease having a special construction adapting it to cooperate with a portable holder so that the container performs the function of a barrel of a grease gun. In this way I avoid the handling of the grease from the original package to the grease gun, as the entire container is set up in the holder and the grease is then forced out of it as desired.

Further objects of the invention will appear hereinafter.

The invention consists in the novel method and features, and in the general combination of parts to be particularly described hereinafter, all of which contribute to produce a simple and efficient portable holder for grease-containers. A preferred embodiment of my invention will be particularly described in the following specification, while the broad scope of my invention will be pointed out in the appended claims.

In the drawing:

Figure 1 is a front elevation of a portable holder embodying my invention, some of the parts being broken away and the grease-container being shown partially in longitudinal section;

Figure 2 is a side elevation, certain parts being broken away;

Figure 3 is a cross section through the device taken about on the line 3—3 of Figure 2;

Figure 4 is a plan of a bevel gear which

constitutes one of the working parts of the device;

Figure 5 is a cross section through the frame about on the line 5—5 of Figure 1, with the plunger of the device raised, and particularly illustrating means for securing the upper end of the container and for guiding the plunger into the container;

Figure 5^a is a section taken on the line 5^a—5^a of Figure 5; and

Figure 6 is a vertical section taken through the lower end of the grease-container.

The frame of the device comprises a base plate 1 adapted to rest upon the floor or upon the ground, from which two opposed frame members 2, 2 extend upwardly, the same being preferably in the form of two A-frames, the cap piece of the A-frames being formed by a head plate or bracket 3 secured to the frame members 2.

I provide suitable means for securing the grease-container in the frame, and construct the same so as to operate as a holder for a flexible tube 4 for directing the grease from the container 5 which is of cylindrical form, as shown, and provided near its lower end with a discharge nipple 6 normally covered by a removable cap 7. The tube holder is in the form of a saddle 8 forming one-half of a split ring (see Figure 3) the other section 9 of which is movable toward or from the tube holder 8. The tube holder 8 is provided with a large nipple 10 which receives the discharge nipple 6 and to this nipple 10 the discharge tube 4 is secured. The tube holder 8 is rigidly attached to the upper side of the base plate 1 by the section 9 which cooperates with it and is movable to and fro by means of a clamping screw 11 which has threaded engagement with a bracket plate 12 (see Figure 3) the inner end of the screw 11 having a swivel connection with a bracket plate 13 on the side of the yoke or section 9. When the screw 11 is operated the clamping yoke or section 9 is guided by means of guide pins 14 which run in slots 15 in the plate 1.

Near the upper portion of the frame and below the head plate 3 I provide means for securing the upper end of the container, and this means preferably operates as a relatively fixed guide to center and guide the plunger 16 as it moves into the upper end of the container. For this purpose I provide two oppositely disposed bars 17 and 110

18 (see Figure 5) the middle portions of which are slightly bowed to receive opposite sides of the container. Furthermore, each of these bars is provided with a rabbet 5 groove 19 (see Figure 5^a) which forms a socket to receive the upper edge of the container, and the inner face 20 of each of these bars is flush with the inner face of the container; and above this point each bar 10 is formed with an inclined or flared lip 21. These lips will engage the edges of the plunger 16, and operate as guides for it as it passes into the container. The bar 17 is rigidly fixed in position, but the bar 18 is 15 secured by a hinge 22 which enables it to be swung outwardly to permit the container to be put in place. The outer end of the bar 18 may be secured to its corresponding frame member 2 by means of a small wing-nut 23.

Any suitable means may be provided for advancing the plunger into the container. As illustrated the plunger is carried on a stem 24 which is threaded so as to operate 25 as a feed screw to be rotated by means of a bevel gear 25, which bevel gear carries a spline 25^a running in a longitudinal groove 24^a in the stem or rod 24. The head plate 3 is screw threaded to fit the threads of the 30 plunger rod or stem 24 so that as the bevel gear 25 rotates and rotates the rod, the plunger will be advanced into the container. The bevel gear 25 may be rotated at will through the medium of a bevel gear 26 carried on a shaft 27 which may be rotated by a crank 28.

The container usually carries about twenty-five pounds of grease; in order to indicate or measure the amount of grease 40 discharged from the same at one operation I provide a scale bar 29 which extends up from the head plate 3 substantially parallel with the stem or screw 24 and on the upper end of the stem or screw 24 I provide a 45 pointer 30 which is attached to the end of the screw by a swivel connection 31. The extremity of this pointer runs in the slot 32 in the scale bar 29. As the pointer descends it indicates the amount of grease 50 which has been discharged.

In using the device it may be set upon the ground or the floor of the garage, and the tube 4 arranged so that it will deliver the grease into the differential casing, or at 55 any other point desired.

In practice I furnish containers to garages or automobile users and these containers may carry any quantity of grease desired. In order to use the grease it is simply necessary to set the container up in the portable holder so that it operates as a cylinder or barrel to co-operate with the plunger to effect the forcing of the grease from the container and through the hose or tube 4.

65 It is understood that the embodiment of

the invention described herein is only one of the many embodiments my invention may take, and I do not wish to be limited in the practice of my invention nor in my claims, to the particular embodiment set forth. 70

What I claim is:

1. A portable holder for a grease-container comprising the combination of a frame, clamping means carried by the frame for securing the grease-container therein, a plunger guided on the frame in substantial alignment with the position of the container, means for advancing the plunger into the grease container, and relatively fixed means supported on the frame for 75 guiding the plunger into the mouth of the container.

2. A portable holder for a grease-container, having a discharge nipple at one end thereof, comprising the combination of a frame, means for securing the grease-container in the frame, means on the frame for forcing the grease from the container and through the discharge nipple thereof, tube-holding means, means for securing the latter 90 over the discharge nipple, and a tube carried thereby for directing the grease from the container.

3. A portable holder for a grease-container, comprising the combination of a frame, a plunger guided on the frame, clamping means including a pair of bars mounted on the frame and having lips for engaging over the sides of the grease-container for holding the same and for guiding 100 the plunger into the container, and means for advancing the plunger.

4. A portable holder for a grease-container having a discharge nipple at one end thereof, comprising the combination of a frame, means for securing the grease-container in the frame, means on the frame for forcing the grease from the container and through the discharge nipple thereof, tube holding means including a saddle adapted 110 to seat on the side of the container and having a tube-carrying nipple receiving the discharge nipple and a flexible tube carried by the latter nipple for directing the grease from the container. 115

5. A portable holder for a grease container having a discharge nipple at one end thereof, comprising the combination of a frame, means for securing the grease-container in the frame, means on the frame for 120 forcing the grease from the container and through the discharge nipple thereof, tube holding means in the form of a split ring with means for clamping the same over the discharge nipple, and a tube carried by the 125 split ring adjacent the discharge nipple for directing the grease from the container.

6. A portable holder for a grease-container, comprising a base plate and a head plate with frame bars connecting the same, means 130

- for supporting the end of the container at the base plate, a plunger having a stem guided through said head plate, means carried by the frame bars for securing the end of the container, and presenting guide lips to engage the edge of the plunger, operating as guides for the plunger in entering the container, and means for advancing the plunger.
- 5 7. A portable holder for a grease-container, comprising a base plate and a head plate with frame bars connecting the same, means for securing the end of the container at the base plate, a plunger having a stem guided through said head plate, means carried by the frame bars for securing the end of the container, and having guide lips to engage the edge of the plunger, operating as guides for the plunger in entering the container,
- 10 20 and means for advancing the plunger, a scale carried by the head plate extending substantially parallel with the side of the plunger, and a pointer carried by the stem co-operating with the scale to measure the amount of grease forced from the container by the plunger.
- 15 25 8. A portable holder for a grease-container, comprising a base plate, a pair of op-
- posed A-frames mounted on the base plate, a head plate attached to the upper ends of the A-frames, tube holding means carried at the base plate for clamping the lower end of the container, a tube carried thereby for directing the grease away from the container, a plunger having a stem guided through the head plate, means mounted on the A-frames for securing the upper end of the container and for guiding the plunger into the same, and means for advancing the plunger.
- 30 35 40 9. A portable holder for a grease-container having a discharge nipple at one end thereof, comprising the combination of a frame including a base plate, a tube holder secured to the base plate, in the form of a saddle carrying a tube to receive grease from the discharge nipple, a yoke guided on the base plate and co-operating with the saddle to secure the container, means for moving the yoke toward or from the saddle, a plunger guided on the upper part of the frame, and means for advancing the same into the container.
- 45 50 In testimony whereof, I have hereunto set my hand.

ARRELIOUS M. McSPADDEN.
